UNITED STATES PATENT OFFICE

159,496

HOSIERY ENVELOPE

Alfred Lindermuth, Chicago, Ill., assignor to
Traver Corporation, Chicago, Ill., a corporation
of Illinois

Application January 6, 1949, Serial No. 87

Term of patent 14 years

(Cl. D58—2)

To all whom it may concern:

Be it known that I, Alfred Lindermuth, a citizen of the United States, residing at Chicago, in the county of Cook and State of Illinois, have invented a new, original, and ornamental Design for a Hosiery Envelope, of which the following is a specification, reference being had to the accompanying drawing, forming part thereof.

The single figure of the drawing is a front view of a hosiery envelope showing my new design. The article is substantially thin and flat. The back of the envelope is plain.

I claim:

The ornamental design for a hosiery envelope, as shown and described.

ALFRED LINDERMUTH.
